DRAFT CONTROLLING AND BACK DRAFT
DIVERSION DAMPER DEVICE FOR FURNACESPaul A. Viola and Joseph A. Viola,
Bridgeport, Conn.

Application May 4, 1948, Serial No. 24,954

5 Claims. (Cl. 126—307)

1

This invention relates to a draft control for furnaces. It could be used with practically any type of furnace, but is designed primarily for oil or gas furnaces, and has for an object to provide a simple and effective device for preventing the downdraft from the chimney passing back into the furnace to possibly blow out the flame or force the gases or products of combustion out into the room.

Another object is to prevent the circulation of cooling air through the furnace to absorb heat and carry it up the chimney when the burner is not operating.

With the foregoing and other objects in view, we have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a partial side elevation and partial section showing use of the device in a furnace;

Fig. 2 is a longitudinal vertical section through the device taken on substantially the line 2—2 of Fig. 4;

Fig. 3 is a horizontal longitudinal section taken substantially on line 3—3 of Fig. 4, and

Fig. 4 is an end view looking from the left of Fig. 2.

A furnace of any desired type is indicated at 5, with the usual smoke pipe 6 and any type of oil burner indicated diagrammatically at 7. It is, however, to be understood this is shown merely by way of example, as the device may be used with other types of burners, such, for example, as gas or coal burners. In the pipe is the usual thermostat 8 operating limit switch 9 to turn off the burner when the heat reaches a certain amount, and mounted in this pipe, preferably in the last section as it enters the chimney 10, is our device indicated as a whole at 11.

The device comprises a section of stove pipe 12 adapted to be inserted at the outlet end in the opening to the flue of the smoke-stack or chimney, and at its other end telescoping with the next standard stovepipe section 6. Within this section 12 is a tapered section 13 which may be made of the sheet metal used for making standard stovepipe and the section 12, and this tapered section is of a size so that its larger end 14 fits and is secured in the section 12 adjacent the end nearest the furnace, with its outlet or smaller end 15 adjacent the discharge end of the section 12. 55

2

This outlet is controlled by a light hinged damper 16 pivotally mounted on the top of the tapered section by any suitable means, such, for example, as a substantially U-shaped bracket 17 which may be secured by any suitable means on the top of the tapered section.

The damper is mounted on a pivot rod 18 extending at one end through the side of the section 12, where it is bent laterally to form a rearwardly extending arm 18a on which is adjustably mounted a counterweight 19 which is adjustable along the rod and may be secured in any adjusted position by the set screw 19a. The rod is formed with an intermediate bend 20 to limit forward movement of weight 19 so that should the weight 19 become loosened or should a child or someone adjust it on the rod, it could not move nearer than this bend to the pivot, so that the damper could not overbalance this weight sufficiently that the damper would not open by draft from the furnace. There may be a small weight 21 mounted in the damper if it is found the damper itself is not of sufficient weight for the counter-balancing effect, and although the damper 5 may be of other shapes it is preferably substantially conical as shown.

The weight 19 is so adjusted that with no fire in the furnace the damper 16 will just close, so that a very light draft will open the damper, as indicated by the dotted line in Fig. 2, as soon as the burner is lighted or becomes operative, but any down or backdraft will close this damper so that it will not blow or flow back into the furnace to blow out the flame of the burner or to force the products of combustion or other gases out into the room. To further assist this action, the outer section 12 is provided with openings 22 on opposite sides and just forwardly of the larger or entrance end of tapered section 13, so that the downdraft flowing toward the furnace, after closing the damper 16, will pass out through these openings 22. These openings also permit air to pass into the pipe during normal operation to help control the draft and to keep it more uniform.

A still further important operation and effect of this device is that when the burner is not operating, as for example, when the temperature has reached a certain limit, as effected by the usual automatic thermostat controls, this damper closes and prevents the flow of cold air through the furnace and up the chimney, which flow of cold air would, of course, have a cooling effect on the furnace and carry a considerable amount of heat up the chimney. It therefore effects a great-

er efficiency in operation of the furnace and a material saving in fuel by preventing this loss up the chimney. This, in addition to the safety features as described and better control of the draft, has made this device very effective in actual use. Due to its simplicity it can be manufactured at relatively low cost and is easily installed in the smoke pipe.

Having thus set forth the nature of our invention, we claim:

1. A draft control for furnaces comprising a section of stove pipe adapted to form a portion of the smoke pipe from the furnace to the chimney, a tapered section in the first section arranged with its larger end fitting the inside of the first section in substantially gas tight relationship therewith and its smaller end spaced substantially inwardly of the inner surface of the first section, said tapered section being hollow and open at both ends to provide a gas passageway entirely therethrough, a pivoted damper at the smaller end of the tapered section, means balancing the damper to swing outwardly away from this end under the influence of a draft from the furnace and to be swung by a back draft to close the opening upon the occurrence of a reverse draft, and the first section being provided with air inlet means leading to the space between this section and the tapered section.

2. A draft control for furnaces comprising a section of stove pipe adapted to form a portion of a substantially horizontal smoke pipe leading from the furnace to the chimney, a tapered section in the first section open at both ends to provide a gas passageway entirely therethrough and arranged with its larger end forming the inlet end and the smaller end the outlet, the larger end fitting the inside of the first section in substantially gas tight relation therewith and the smaller end spaced substantially inwardly of the inner surface of the first section, a pivoted damper over the smaller outlet end, a lateral arm connected to the damper, a balance weight adjustably mounted on said arm, said damper being arranged to swing outwardly from said smaller end under influence of a draft from the furnace and to be swung back to close the opening by a back draft from the chimney, and the first section being provided with air inlet openings leading to the space between this section and the tapered section.

3. A draft control for furnaces comprising a section of stove pipe adapted to form a portion of a substantially horizontal smoke pipe leading from the furnace to the chimney, a tapered section in the first section open at both ends to provide a gas passageway entirely therethrough and arranged with its larger end fitting the outer section in substantially gas tight relationship therewith and its smaller end forming the outlet spaced substantially inwardly of the inner surface of the first section, a damper over the outlet end, means pivotally mounting said damper on the tapered section to swing outwardly away from said smaller end under the influence of a draft from the furnace and to be swung by a back draft

to close the opening in said smaller end upon the occurrence of a reverse draft, said mounting means comprising a pivot rod including a laterally extending arm, a balance weight adjustably mounted on the rod, said rod being provided with a stop means for said weight between the weight and pivot portion of the rod to limit movement of the weight toward this portion, and the outer section being provided with air inlet openings leading to the space between this section and the inner tapered section.

5. A draft control for furnaces comprising a section of stove pipe adapted to form a portion of the smoke pipe from the furnace to the chimney, a tapered section in the first section open at both ends to provide a gas passageway entirely therethrough and arranged with its larger end fitting in the outer section in substantially gas tight relationship therewith, and its smaller end spaced substantially inwardly of the inner surface of this first section, a pivoted damper closing the smaller end, means balancing the damper so that it will move outwardly away from said end to open position under the influence of a draft from the furnace and will be swung back to close the opening upon the occurrence of a reverse draft from the chimney, and the outer first section being provided with air inlet openings adjacent the larger end of the tapered section leading to the space between the outer and tapered sections.

6. A draft control for furnaces comprising a section of stove pipe adapted to form a portion of the smoke pipe from the furnace to the chimney, a tapered section in the first section open at both ends to provide a gas passageway entirely therethrough and arranged with its larger end forming the inlet end and the smaller end the outlet, the larger end fitting the inside of the first section in substantially gas tight relationship therewith and the smaller end spaced substantially inwardly of the inner surface of the first section, a pivoted damper over the smaller outlet end, a lateral arm connected to the damper, a balance weight adjustably mounted on said arm, said damper being arranged to swing outwardly away from said smaller end under the influence of a draft from the furnace and be swung by a back draft to close against said end upon the occurrence of a reverse draft from the chimney, and the outer section being provided with air inlet openings adjacent the larger end of the inner section leading to the space between the outer and inner sections.
